COMPRESSOR AND PUMP.

Application filed September 19, 1923. Serial No. 663,594.

The invention to be hereinafter described relates to air compressors or pumps, and more particularly to means for utilizing the velocity or kinetic energy of the piston of the air compressor or pump, thereby materially to increase the efficiency thereof. The fluid acted on may be either a gas or a liquid.

A piston moving within a cylinder has velocity which in one type of compressor is absorbed and distributed as energy from one stroke of the piston to the next stroke by means of a fly wheel on a crank shaft connected to the piston by a connecting rod. Since the motion of the fly wheel is continuous in the same direction of rotation, the velocity energy thereof is not completely lost, but to a large extent is conserved and returned to the piston.

When a piston moving within a cylinder is used to transmit motion to a liquid or to compress a gas, the velocity energy of the piston is transmitted to the liquid or gas. If the liquid or gas acted upon is allowed to escape through an outlet in the cylinder, it carries with it the velocity energy received from the piston. Usually the cylinder outlet is relatively small as compared to the cross section of the cylinder, and the velocity of the fluid is increased in passing through the outlet. If a gas is compressed by the cylinder and delivered into a region of low pressure, its velocity is still further increased by its diffusion.

Under certain conditions in practice, the fluid moved by the piston is brought to rest eventually without transmitting its motion to another movable body. Under these conditions the velocity energy of the fluid is in direct opposition to a stationary body, such, for example, as a storage tank or container. This results in compression of the gas and transformation of kinetic energy into heat energy.

The present invention provides means for utilizing or saving velocity or kinetic energy of the fluid acted upon by the piston. In carrying the invention into practical effect, in the present instance, the movement of the fluid by the piston is transmitted to a column of mercury in a tube, and on each stroke of the piston the mercury column is elevated in the tube, and at the end of each stroke, the mercury column is allowed to drop under influence of gravity, thereby to

move the liquid or compress the gas which elevated the column. Since mercury has high specific gravity and a low coefficient of friction, it drops quickly with substantial force.

When the mercury column has been raised, it has potential energy because of the influence of gravity thereon, and when the column drops, its potential energy is converted by gravity to kinetic energy.

When the fluid is moved by the piston, its velocity or kinetic energy is transmitted in a large extent to the mercury column, and is yieldingly opposed by the influence of gravity on the mercury column. Thus, by the cooperation of the mercury column with an air compressor or pump, the efficiency thereof may be materially increased.

The character of the invention may be best understood by reference to the following description of one good form thereof shown in the accompanying drawings, wherein:

Fig. 1 is a side elevation of apparatus embodying the invention, certain parts being shown in section;

Fig. 2 is a perspective view of one of the valves provided in the pipe for conducting the fluid from the air compressor;

Fig. 3 is a longitudinal section through the valve shown in Fig. 2;

Fig. 4 is a section taken on line 4—4 of Fig. 3;

Figs. 5, 6 and 7 are diagrams to be referred to; and

Fig. 8 is a modification to be referred to.

The apparatus shown herein as one good form of the invention, comprises an air compressor which may be of well known construction and therefore, it is unnecessary to show and describe the same in detail herein. Briefly, this air compressor comprises a cylinder 1 containing a piston 3 connected by a rod 5 with a cross head 7 adapted to slide in a guide 9. A connecting rod 11 extends from the cross head to a crank 13 on a shaft 15 journalled in bearings in a casing 17. The crank is counterbalanced by a weight 19. Fast on the shaft 15 is a fly wheel 21, and also fast on the shaft is a pulley 23 adapted to be driven by a belt from any suitable source of power.

The heads of the cylinder 1 are provided with water jackets, and said cylinder is provided with inlet valves 25 and discharge 110

valves 27. The compressor is double acting, and on each stroke of the piston, air is drawn into the cylinder and discharged therefrom. The compressed air may be delivered through a pipe 29, which in the present instance of the invention, leads to a storage tank 31.

Connected to the pipe 29 is a tube 33, in the present instance, of U-shaped form and having legs 35 and 37. The upper end of the leg 35 is connected to the pipe 29, and the other leg is extended upward, in the present instance, somewhat above the pipe 29. The tube 33 contains a mercury column 39.

Suitable valve means may be provided for controlling the delivery of the fluid from the compressor to the U-tube, and from the U-tube to the tank, and in the present instance, valves 41 and 43 are provided in the pipe 29 at opposite sides of the point of connection of the U-tube therewith. Since these valves are similar in construction, a description of one will suffice for both.

This valve comprises a body 45 (Figs. 2, 3 and 4) having necks 47 and 49 threaded for connection with the pipe 29. The body is provided with a head 53 having a stuffing box 55, and a head 57 having a stuffing box 59. Mounted in the body is a cylindrical plug 61 having a transverse passage 63 which may be brought into or out of registration with the necks 47 and 49 on rotative adjustment of the plug.

A shaft 65 projects through the head 53, and is connected by a pin 67 with the plug. On the outer end of the shaft is an arm 69 secured by a nut 71. To indicate the rotative adjustment of the plug, an index 73 may be secured to the shaft 65 and moved over a graduated dial 75.

Means will be provided to impart longitudinal adjustment to the plug 61, thereby to vary the effective opening of the passage 63. This means comprises a shaft 77 threaded into the head 57 and having its inner end connected by a swivel 79 to the plug. The outer end of the shaft 77 is provided with a hand wheel 81 adapted to be held in different positions of rotative adjustment by a finger 83 secured to the body and adapted to enter in one of a series of notches 85 in the hand wheel. The finger 83 has a graduated scale 87 adapted to be read in connection with the periphery of the hand wheel. The construction is such that on manual rotation of the hand wheel, the plug will be shifted longitudinally with respect to the body, thereby to cause the effective opening of the passage 63 to be varied.

Suitable means may be provided automatically to control the valves 41 and 43. This means, in the present instance of the invention, comprises a cam 89 fast on the crank shaft 15 referred to, and cooperating

with a follower 91 on a bell-crank 93 carried by a bracket 95, said bell-crank being pressed by a coil spring 97 to hold the follower 91 in engagement with the cam. The bell-crank is connected by a link 99 with the arm of the valve 41, and the arms of the valves 41 and 43 are connected by a link 101. The cam 89 has a pair of diametrically opposed depressions 89^a in the periphery thereof. The construction is such that twice in each complete rotation of the cam, the follower will drop into the depressions 89^a, and thereby shift the valves in one direction, and shortly thereafter the follower will move out of the depressions, and thereby shift the valves in the opposite direction.

The valve arms are so mounted on their shafts that they are in vertical positions when the valves are open, and are in oblique positions when the valves are closed. When the valve 41 is open, the valve 43 is closed, as indicated in Fig. 1.

The operation of the apparatus is as follows: When the compressor piston 3 is ready to move toward the right (Fig. 5), the valve 41 is open, and the valve 43 is closed. As the piston moves toward the right, the fluid acted upon will be forced through the pipe 29 into the tube, thereby forcing the mercury down in the leg 35 and up in the leg 37. Since the fluid does not meet an immovable body, but meets the mercury column which is yieldable, the velocity energy of the fluid is transmitted to the mercury column, and the elevation of the mercury column in the leg 39 is partially due to the velocity energy, and the head thereby produced becomes available as potential energy. The static pressure head of the mercury column is indicated at 103, and the velocity head is indicated at 105 in Fig. 6.

When the piston is at the end of its stroke, and the mercury column head has been produced, the valve 41 is closed, and the valve 43 is opened, thereby allowing the mercury column head to force the fluid into the storage tank 31. Thereupon, the valve 43 is closed, and the valve 41 is opened (Fig. 7), so that when the piston commences its stroke to the left, the pressure and velocity energy of the fluid will be transmitted to the mercury column, with the effect above described.

Under certain conditions it may be desirable to provide a chamber 107 in the pipe 29 at a point between the compressor cylinder 120 and the valve 41. This chamber increases the amount of fluid between the compressor and the mercury column and contributes to smoothness of operation.

Because of the high specific gravity and small coefficient of friction of the mercury column, the latter will drop quickly when released, and therefore, will not prevent operation of the air compressor at high speed.

It will be understood that the mercury 130

column employed will have a mass and height sufficiently great to receive the force of the compression of the fluid produced by the compressor piston without forcing of the mercury column up out of the open end of the leg 37.

If the fluid moved by the compressor piston is opposed by a stationary body, the kinetic energy of the fluid is transformed 10 into heat energy. On the other hand, if the fluid acts upon a movable body, such, for example, as the mercury column of the present apparatus, velocity energy is transmitted as velocity energy to the movable 15 body or column.

There are few substances which have less friction on hard surfaces and are more easily movable thereover than mercury. Therefore, the fluid advanced by the 20 compressor piston in striking the surface of the mercury column, imparts a great proportion of its velocity energy to the mercury column. This velocity energy causes the mercury column to rush upward in the leg 37 of the U-shaped tube, and as the column moves upward, it is constantly acquiring 25 potential energy until eventually the action of gravity on the column overbalances the kinetic energy of the fluid. Then the mercury column has acquired and possesses a 30 certain amount of potential energy due to elevation of the column, and this potential energy acts upon the fluid.

When the potential energy of the mercury 35 column has become greater than the potential energy of the fluid represented by pressure, the mercury column descends in the tube leg 37 until the two energies are equalized. On the next stroke of the compressor 40 piston, the above cycle of operations is repeated.

In Fig. 8 is shown a modification in which the leg 37 of the mercury tube is closed by a dome 109, and a shorter column and mass 45 of mercury is employed. In operation, the mercury column will be forced intermittently upward in the tube leg 37, thereby compressing the body of air in the leg and dome above the mercury column. When the valve 50 43 is opened the air thus compressed and the influence of gravity on the column will force the air back of the mercury column in the tube leg 35 into the storage tank.

It will be understood that the invention is 55 not limited to the specific embodiment shown, and that various deviations may be made therefrom without departing from the spirit and scope of the appended claims.

What is claimed is:

60 1. The combination with an air compressor, of a receiver for the compressed air, a pipe extending from the air compressor to the receiver, a tube communicating with said pipe at a point between the compressor and the receiver and containing a mercury col-

umn adapted to be elevated on strokes of the compressor, thereby to store up the velocity energy of the air set in motion by the strokes of the compressor, a valve operable to permit compressed air to flow from the 70 compressor into the pipe and tube, or to prevent compressed air from flowing into the pipe and tube, a valve operable to permit the compressed air to be forced by the mercury column into the receiver, or to prevent 75 the compressed air from being forced by the mercury column into the receiver, and means automatically to operate said valves.

2. The combination with an air compressor, of a tube communicating with the air compressor and containing a mercury column adapted to be elevated on strokes of the compressor, thereby to store up the velocity energy of the air set in motion by the strokes of the compressor, a valve operable to permit the compressed air to pass from the compressor into the tube, and to prevent compressed air from passing from the compressor to the tube, a valve for permitting the compressed air to be forced by the mercury column from the tube, or to prevent the compressed air from being forced by the mercury column from the tube, and means automatically to operate said valves.

3. The combination with an air compressor, of a receiver for the compressed air, a pipe extending from the air compressor to the receiver, an upstanding U-shaped tube communicating with the pipe and containing a mercury column movable downward in one of the legs of the U-shaped tube and upward in the other leg thereof on compression strokes of the compressor, thereby to store up the velocity energy of the air set in motion by the strokes of the compressor, 95 valve means for the pipe, and means automatically operated by the compressor to operate said valve means to deliver air compressed by the strokes of the compressor to the mercury column of the tube to elevate 100 the mercury column and then admit the compressed air under the pressure of said column to the receiver.

4. The combination of a cylinder, a piston therein adapted to act upon a fluid, a receiver, a pipe extending from the cylinder to the receiver, a U-shaped tube having one end connected to the pipe at a point between the cylinder and the receiver, said tube containing a mercury column, and valve means 115 for permitting the fluid to pass from the cylinder through the pipe into one of the legs of the U-shaped tube, thereby to force the mercury up in the other leg of the tube, said valve means having provision for allowing the mercury to force the fluid from the tube into the receiver.

5. The combination of a cylinder, a piston therein adapted to act upon a fluid, a tube communicating with the cylinder and con-

taining a mercury column adapted to be elevated by the fluid on strokes of the piston, thereby to store up the velocity energy of the fluid set in motion by the strokes of the piston, valves for controlling passage of the fluid from the cylinder to the tube, and passage of the fluid from the tube, and means automatically to operate said valves having provision for simultaneously closing one of said valves and opening the other of said valves.

6. The combination of a cylinder, a piston therein adapted to act upon a fluid, a container communicating with the cylinder and having therein a body of mercury adapted to be elevated by the fluid on strokes of the piston, thereby to store up velocity energy of the fluid set in motion by the strokes of the piston, and a valve mechanism for controlling passage of the fluid from the cylinder to the body of mercury in the container and passage of the fluid from the container.

7. The combination of a cylinder, a piston therein adapted to act upon a fluid, a storage tank, a container communicating with the cylinder and the storage tank and having therein a body of mercury adapted to be elevated by the fluid on strokes of the piston, thereby to store up in the body of mercury velocity energy of the fluid set in motion by the strokes of the piston, and a valve mechanism for automatically controlling passage of the fluid from the cylinder into the container against the body of mercury, and pas-

sage of the fluid from the container into the storage tank.

8. The combination of a cylinder, a piston therein adapted to act upon a fluid, a tube communicating with the cylinder and containing a mercury column adapted to be elevated by the fluid on strokes of the piston, thereby to store up velocity energy of the fluid set in motion by the strokes of the piston, said tube having a closed end and a space between the mercury column and the closed end of the tube containing air compressed by the mercury column when the latter is elevated in the tube, valve means for controlling passage of the fluid from the cylinder to the tube and passage of the fluid from the tube, and means automatically to operate said valve means.

9. The combination of a cylinder, a piston therein adapted to act upon a fluid, a container communicating with the cylinder and having therein a body of mercury and an air space, the body of mercury being adapted to be moved by the fluid on strokes of the piston against the pressure of the air in said space, thereby to store up velocity energy of the fluid set in motion by the strokes of the piston, and a valve mechanism for automatically controlling passage of the fluid from the cylinder to the body of mercury in the container, and passage of the fluid from the container.
